UNITED STATES PATENT OFFICE.

SYDNEY ERNEST RUTTER, OF LONDON, ENGLAND, ASSIGNOR TO DOROTHY JAY HARRIS,
OF LONDON, ENGLAND.

MECHANISM FOR STROPPING OR HONING RAZOR-BLADES.

1,308,196.

Specification of Letters Patent.

Patented July 1, 1919.

Application filed December 20, 1917. Serial No. 208,175.

To all whom it may concern:

Be it known that I, SYDNEY ERNEST RUTTER, a subject of the King of Great Britain, residing at 70 Shenley road, Camberwell, 5 London, S. E. 5, England, have invented certain new and useful Improvements in Mechanism for Stropping or Honing Razor-Blades, of which the following is a specification.

10 This invention relates to mechanism for the stropping or honing of razor blades, and it has for its object to enable blades such as are used more particularly with safety razors, to be sharpened in a simple, safe and 15 reliable manner, and for this purpose to provide a mechanism adapted for use either separately or combined with any safety razor, without substantially increasing the cost of the latter in either case.

20 To this end this invention relates more especially to a stropping mechanism of the kind in which provision is made of a rotatable blade holder and a rotary actuating member, arranged so that the latter by frictional reciprocation on a stropping or honing surface causes the edge of the blade on both sides to be moved alternately into contact with the strop by oscillating the blade holder at each end of its reciprocatory 25 movements.

Now, according to this invention the rotatable blade holder forms a separate and readily detachable part so that it may be removed from its actuating mechanism and in some cases be used with the blade in the shaving position and removed therefrom into the stropping position or vice versa. Moreover, the rotary actuating member, by preference jointly with a guide member, 30 either forms part of, or is connected to a separate handle, or it may form part of, or be connected to the handle of the safety razor.

These and other characteristic features of the invention will be more fully described with reference to the accompanying drawings, in which:

Figure 1 shows the stropping mechanism as a separate contrivance in plan view.

Fig. 2 shows separately the blade holder 50 adapted to hold "Gillette" blades.

Fig. 3 is a view at right angles to Fig. 1, showing the blade holder of Fig. 2 in position in the stropping mechanism.

Fig. 4 is a section on the line IV—IV of 55 Fig. 2.

Fig. 5 is a section on the line V—V of Fig. 2.

Fig. 6 shows in plan view a modified construction of the stropping mechanism with 60 the blade and holder or actuator partly removed.

Fig. 7 is a right angle view of Fig. 6, partly in section.

Fig. 8 is a top plan view of Fig. 6 and 65

Fig. 9 shows in a transverse section of Fig. 6 the use of the stropping device and the triangular arrangement of its principal parts.

In the above drawings all figures are 70 drawn on an enlarged scale, and similar reference numbers are employed to designate similar parts.

Referring first to Figs. 1 to 4, the stropping mechanism shown comprises a rotary 75 actuator in the form of a friction roll 1, a guide member in the form of a stationary or rotatable cylindrical roll 3, and a rotatable blade holder 2. The friction roll 1 and the guide member 3 are connected at 80 one end to a handle 4 and at the other end to an end plate or bearing 5. The blade holder 2 comprises a cylindrical stem 6 and the holder proper 7. This holder 2, adapted to receive a blade 8 is so arranged that it 85 may be readily attached to, or detached from the stropping mechanism. To this end the stem 6 is provided at one end with a reduced portion or trunnion 9 and at the other end with a central bore 10, the latter being 90 adapted to be slipped over a spring actuated pin 11 arranged in the adjacent handle portion, and the former into an opening 12 arranged in the plate 5. The spring 13 supporting the pin 11 tends to hold this pin in 95 its protruding position, and when the bore 10 is slipped over the pin 11, the stem 6 bearing on a cylindrical socket 14 of the pin

causes the latter to yield in opposition to the spring 13, until the other end 9 of the stem is in position in the opening 12 and the pressure on the pin 11 is relieved. With the blade holder in position, the axes of the parts 1, 2 and 3 form the points of a triangle, as clearly shown in Fig. 9. The roll 1 carries at one end a toothed wheel 15, and the holder has the adjacent end of its stem 5 provided with a pinion 16, so that when the holder is in operative position, the gear wheels 15 and 16 are in engagement one with the other. Of course, these gear wheels 15 and 16 may be replaced by plain friction 10 disks for the same purpose. It will thus be seen more particularly from Fig. 9 that by placing the contrivance upon a friction surface, such as a strop 17, so that the roll 1 and the guide 3 lay flat thereon, and reciprocating the contrivance in the direction of the arrows *a*, *b*, the roll 1 in its alternate rotation will cause by the engagement of the gear wheels 15 and 16 the blade holder 2 to oscillate, and the edge of the blade contained in the holder to be brought on either 15 side alternately into contact with the strop and held therein during the subsequent longitudinal movement until by the reversal of the latter the holder is rocked into its new 20 position. With this mechanism the strop need, therefore, not be first threaded or inserted between the actuating parts, but the stropping or honing may, as will be seen, be readily effected upon any friction surface 25 suitable for the requisite purpose. The plate or bearing 18 to which in the drawings the handle 4 is shown to be connected by a screw socket 19 may, of course, be permanently attached to the handle 4, if desired, 30 as shown for example in Fig. 6 hereinafter more fully described.

From the foregoing it will be readily understood that the holder 2 may be constructed to receive razor blades of any particular make. In Figs. 2, 3, 4, 5 and 6, for instance, the holder is particularly designed for "Gillette" blades. To this end the holder portion proper securely connected to the stem 6 consists of a plate 7 provided with 35 two lugs 20 produced by stamping or in some other known manner, so as to form hook-shaped members, as clearly shown in Fig. 4. One of the transverse edges 21 of the plate is slightly curved, as shown at 21, 40 and provided with a rectangular offset or abutment 22. The blade 8, assumed in this case to be provided with the usual holes 23, is placed over the plate 7 so that the lugs 20 slip into these holes and overlap the edges 45 thereof when the curved edge 21 of the blade adjacent to the flange 22 drops down into engagement with the latter, after which the blade is in position for stropping. As the stropping movement is at right angles to 50 the direction of the lugs 20, the latter hold

the blade securely in this position, although a very small exertion is required to slip the blade off and detach it from the holder after stropping.

In the construction of the stropping mechanism shown in Figs. 6 to 9, the handle 4^a is loop shaped, and, as already indicated in connection with Fig. 4, has the bearing plate 18 permanently attached to it. In this case the bearing plates 5 and 18, however, are much longer than in the previous construction for the purpose of enabling the guide member 3 to be set farther apart from the actuator 1 and thereby to increase the contact surfaces on the strop. In this construction, moreover, one shank of the handle 4^a is shown to form a brace 4^b between the end plates 5 and 18. The stem 6 of the blade holder is of the same construction as before, the central bore 10 arranged in its end again serving to be slipped over a pin or journal 11 while its opposite end or trunnion 9 is adapted to be slipped through the hole 12 in the bearing plate 5. Instead of the spring 13, however, supporting the journal 11 as in the other construction, a flat spring 13^a is arranged on the outer surface of the plate 5, (Fig. 8) so that as the blade holder is put into position or while it is withdrawn, the spring 13 is caused to yield to the trunnion 9 as indicated in Fig. 6 but otherwise to hold the blade holder in its correct position in the stropping device. In this position, as shown in Fig. 9, the blade holder offers the advantage of an enlarged contact surface with the strop the bottom edges 5^a and 18^a of the bearing plates assisting the user in keeping the device in a correct flat position.

It is obvious that numerous modifications are possible to those skilled in the art, both as regards the characteristic features and constructive details of this invention, without departing from the spirit thereof and that this invention, therefore, must not be held to be limited to any of the specific constructions shown and hereinbefore described.

What I claim and desire to protect by Letters Patent is:—

1. A mechanism for stropping or honing 115 razor blades comprising in combination a holding frame provided with bearings, a rotary actuator journaled therein and a rotatable blade holder having one end of its stem provided with a trunnion member adapted 120 to fit a hole in one of the bearings of said holding frame and its other end with a pinion having a central bore adapted to be slipped over a trunnion journal yieldingly arranged in the other bearing thereof.

2. A mechanism for stropping or honing 125 razor blades comprising in combination a holding frame provided with bearings, a rotary actuator journaled therein and a rotatable blade holder detachable therefrom and 130

having a blade holding plate provided with hook shaped lugs and a lateral flange for the engagement with and the seating thereon respectively of a blade, substantially as described.

3. A mechanism for stropping or honing razor blades comprising in combination a rotary actuator, a rotatable blade holder in engagement with and detachable from the actuator, a guide member, bearing plates in which the opposite ends of the actuator, blade

holder and guide member are journaled at the points of a triangle and a handle connected to one of the bearing plates substantially as described.

15

In testimony whereof I have affixed my signature in presence of two witnesses.

SYDNEY ERNEST RUTTER.
